ATTORNEYS.

UNITED STATES PATENT OFFICE.

JOHN B. WEST, OF SYRACUSE, NEW YORK.

SIGNAL-ELEMENT CONSTRUCTION.

Application filed July 24, 1925. Serial No. 45,846.

This invention has for its object a signal element, particularly applicable for direction indicators for motor vehicles of the type shown in the application of George E. Bates,

5 Sr. No. 702,129, filed March 26, 1924, allowed March 12, 1925, which signal element is composed of light material as glass or celluloid of different colors, and the particular object of the invention is the frame signal element, which frame not only unites the parts of different colors and acts as a support for the signal element, but also increases the visibility of the indicator member or arrow of the signal element by setting it

10 off or contrast it, particularly at night from the remaining portions of the signal element.

The invention consists in the novel features and in the combinations and constructions hereinafter set forth and claimed.

20 In describing this invention reference is had to the accompanying drawings in which like characters designate corresponding parts in all the views.

Figure 1 is a face view of this signal element.

25 Figure 2 is a vertical sectional view taken centrally on Fig. 1, a portion of the actuating means and of the enclosing case being also shown.

30 Figures 3 and 4 are respectively detail views of the disk member and the indicator member of the signal element.

This signal element comprises generally an outer discoidal member of transparent or 35 translucent material of a signal color as a tail light color or red, the disk having an opening for the indicator member, and the indicator member, as an arrow covering the opening and being of different color from the disk member, as white or yellow, and a support or frame for the signal element by which the disk member and indicator member are united and by which the signal element can be mounted upon means for moving it about an axis, which frame or support is so located as to increase the visibility and contrast between the disk and arrow particularly at night.

1 designates the disk member having an 40 arrow-shaped opening 2 therein, the disk member being preferably of celluloid or fiberloid, although it may be of any trans-

parent or translucent material as glass. As this signal member is intended to be used in most instances as a tail light the disk 1 is 55 red.

3 is the indicator member which is in the form of an arrow, arranged to cover the opening 2 in the disk member 1, the outer margin of the arrow 3 lapping the margin 60 of the disk 1 around the arrow-shaped opening 2.

The frame 4 of the signal member acts to unite the disk 1 and the arrow 3, and is in the form of a border around the arrow 65 3, preferably on the outer side thereof. This frame is preferably of thin metal and is secured to the overlapping margins of the arrow 3 and the disk 1 by fastening members as rivets 5, passing through holes in the 70 frame 4 and through alined holes 6 and 7 in the lapping margins of the disk 1 and arrow 3. Preferably in order to give further rigidity to the frame but more particularly to give greater visibility to the arrow by preventing the red light through the disk 1 from spreading onto the yellow or white arrow, the frame is formed along its outer margin with an angular flange or shield 8 extending entirely around the frame. If 80 desired an additional arrow-shaped frame member may be provided on the rear side of the disk 1, but without the flange 8, this being secured in position by the same rivets or fastening members that secure the frame 85 4, disk member 1 and arrow 3 together.

This signal is designed to normally stand with the arrow pointed upwardly and to be turned a quarter of a turn to the right or to the left to indicate that the vehicle 90 is to make a right or left turn, and the signal member is so moved about its axis by any suitable actuating means including a shaft 9 having a radial arm 10 spaced-apart from the signal element 1, the arm 10 having a 95 forwardly extending arm 11 at its outer end, the arm having lugs 12 which are secured to the frame at the point of the arrow or at any other point by some of the rivets 5.

The arm 10 is so arranged to prevent the 100 throwing of shadows on the signal element from the lamp 13.

It will be understood that the signal element, lamp, and actuating mechanism is

mounted in a suitable case 14, having a clear transparent window 15 in front of the signal member 1.

Owing to the frame 4, the disk 1 and arrow 3 are not only firmly united and a firm support provided for attaching the signal element to the actuating means, but also the arrow is clearly and sharply visible at a comparatively greater distance owing to the border around it formed by the frame, and further owing to the flange or shield 4 the contrast between the red disk and the yellow or white arrow is maintained at as great a distance as it is necessary for the arrow to be visible.

Furthermore such border or frame permits a much smaller arrow to be used and be visible at the required distance, than if such border and frame were not used.

20 By this construction of signal element, the signal can be embodied in the limits or area of the tail light lens, and leave ample tail light, and at the same time the arrow is clearly and sharply visible at any distance, than it is necessary to be visible in order to give an effective signal.

What I claim is:—

1. A signal element, comprising a transparent background disk movable about an axis, and a transparent pointer of a different color from the disk, the pointer being movable about an axis with the disk, and a frame for the signal element, the frame being of the same outline as the pointer, the disk and pointer being secured to the frame, and arranging to form a border therefor.

2. A signal element, comprising a transparent background disk movable about an axis, and a transparent pointer of a different color from the disk, the pointer being movable about an axis with the disk, and a frame for the signal element, the frame being of the same outline as the pointer, the disk and pointer being secured to the frame, and arranged to form a border therefor, and means for rotating the element about its axis, said means being connected to the frame.

3. A signal element, comprising a transparent background disk movable about an axis, and a transparent pointer of a different color from the disk, the pointer being movable about an axis with the disk, and an opaque border around the pointer, the border having an outwardly extending light shielding flange arranged at an angle to the face of the signal element.

4. A signal element, comprising a transparent background disk movable about an axis, and a transparent pointer of a different color from the disk, the pointer being movable about an axis with the disk, and a frame for the signal element, the frame being of the same outline as the pointer, and arranged to form a border therefor, the disk and pointer being secured to the frame, and means for rotating the signal element about its axis, said means being connected to the frame, said frame having a forwardly extending light shielding flange at an angle to the face of the signal element.

5. A signal element, comprising a transparent disk member movable about an axis and having an opening therethrough, a transparent indicator member closing the opening of the disk member, the margin of the indicator member lapping the margin of the disk member around the opening, a frame extending around the indicator member on the outer face of the signal element, and attached to the lapping margins of the disk and indicator member.

6. A signal element, comprising a transparent disk member movable about an axis, and having an opening therethrough, an indicator member covering the opening of the disk member, the margin of the indicator member lapping the margin of the disk member around the opening, a frame extending around the indicator member on the outer face of the signal element, and attached to the lapping margins of the disk and indicator member secured to the frame, and means for rotating the signal element.

7. A signal element, comprising a transparent disk member movable about an axis and having an opening therethrough, an indicator member covering the opening of the disk member, the margin of the indicator member lapping the margin of the disk member around the opening, a frame extending around the indicator member on the outer face of the signal element, and attached to the lapping margins of the disk and indicator member, the frame being located on the front face of the signal element and having a forwardly extending marginal flange.

In testimony whereof, I have hereunto signed my name, at Syracuse, in the county of Onondaga, and in the State of New York, this 15th day of July, 1925.

JOHN B. WEST.
